(57) **ABSTRACT**

Provided herein is a set of card-like structure and connector toys for building; the set comprising one or more card-like structures and one or more end cap connectors, wherein the one or more end cap connectors comprise one or more slots for inserting the card-like structures. Also provided herein is a connector toy or a kit of connector toys; comprising one or more slots for inserting card-like structures for building.

CARD-LIKE STRUCTURE AND CONNECTOR TOYS FOR BUILDING

FIELD OF THE INVENTION

The present invention relates to the field of card-like toy blocks, bricks, structures and/or connectors for building.

BACKGROUND OF THE DISCLOSURE

It is a popular activity for individuals, particularly children, to use toy elements and/or structures for constructing and/or erecting houses and/or buildings and/or villages and/or any desired object. There are, therefore, a wide variety of toy building sets readily available ranging from simple stacking elements to complex connecting and/or interlocking parts. Such sets often comprise a plurality of pieces with connection means used to form toy buildings and/or other miniature structures.

Certain of these types of building sets employ card-like structures, including but not limited to cards and connector pieces, or flat structures with surface protrusions or holes or sheet elements with corresponding grooved coupling studs.

While toy building sets having cards or card-like or flat structures or sheet or panel elements and corresponding connector parts are readily available and may be found, for example in U.S. Pat. Nos. 6,761,609 B1; 2,883,764 A; 3,119,154 A; 2,204,319 A; 298,633 A; 2,131,349 A; 3,747,262 A; 5,215,490 A; 5,895,045 A; 5,015,149 A; 6,997,771 B1; 6,149,485 A; 6,443,798 B1; United States Application Numbers 2002/0090881 A1; 2003/0162374 A1; and 2007/0252332 A1; European Application Number 0761272 A2; and International Application Number WO 1997018875 A1; none of these references disclose the embodiments of the card-like structures and connectors disclosed herein.

Therefore, a toy building set with card-like structures for slotting into corresponding connector pieces provides a simple yet unique and entertaining option for fulfilling an individual's desire to construct buildings and/or objects. Additionally, the toy building set disclosed herein may be advantageously used in conjunction with existing Lego® or other similar building bricks.

All documents and references cited herein and in the referenced patent documents, are hereby incorporated herein by reference.

SUMMARY OF THE INVENTION

The present inventors have designed a toy building set with card-like structures for fitting and/or slotting into corresponding connector pieces providing a simple yet unique and entertaining option for fulfilling an individual's desire to construct miniature buildings and/or objects.

Disclosed herein is a set of card-like structure and connector toys for building; the set comprising: one or more card-like structures and one or more end cap connectors, wherein the one or more end cap connectors comprise one or more slots for inserting the card-like structures.

In another embodiment, the one or more slots are on the one or more end cap connectors in a configuration selected from the group consisting of bottom, top, side, sides, and a combination thereof.

In another embodiment, the one or more card-like structures are flat.

In another embodiment, the one or more end cap connectors comprise a connection pattern.

2

Also disclosed herein is a connector toy for building with card-like structures; wherein the connector toy is an end cap connector comprising one or more slots for inserting card-like structures.

5 In another embodiment, the one or more slots on the end cap connectors are in a configuration selected from the group consisting of bottom, top, side, sides, and a combination thereof.

In another embodiment, the end cap connector comprises 10 a connection pattern.

Also disclosed herein is a kit of connector toys for building with card-like structures; the kit comprising one or more end cap connectors comprising one or more slots for inserting card-like structures.

15 In another embodiment, the one or more slots on the one or more end cap connectors are in a configuration selected from the group consisting of bottom, top, side, sides, and a combination thereof.

In another embodiment, the one or more end cap connectors comprise a connection pattern.

20 In another embodiment, the kit comprises card-like structures.

In other embodiments, the set of card-like structure and connector toys in the preceding paragraphs may additionally comprise Lego® building bricks and/or other similar building bricks.

25 In other embodiments, the set of card-like structure and connector toys in the preceding paragraphs may additionally comprise one or more character figures, one or more designs and/or graphics, and/or one or more character figures corresponding to a design or graphic on the one or more card-like structures and/or end cap connectors.

In other embodiment, the set of card-like structure and connector toys in the preceding paragraphs may incorporate 30 any of the preceding or subsequently disclosed embodiments.

In other embodiments, the connector toy or connector toys in the preceding paragraphs may additionally incorporate 35 any of the preceding or subsequently disclosed embodiments.

The Summary of the Invention is not intended to define the claims nor is it intended to limit the scope of the invention in any manner.

40 Other features and advantages of the invention will be apparent from the following Drawings, Detailed Description, and the Claims.

BRIEF DESCRIPTION OF THE FIGURES

FIG. 1A-1D illustrates perspective top and bottom views 50 of embodiments of the end cap connectors disclosed herein.

FIG. 2A-2B illustrates perspective views of exemplary 55 assembly of an embodiment of the end cap connectors and the card-like structures disclosed herein.

FIG. 3A-3D illustrates side perspective views of an embodiment of the end cap connectors and card-like structures disclosed herein.

FIG. 4A-4C illustrates perspective views of exemplary 60 assembly of card-like structures and end cap connectors and a perspective view of an underside embodiment of an end cap connector disclosed herein.

DETAILED DESCRIPTION

65 The present invention is illustrated in the drawings and description in which like elements are assigned the same reference numerals. However, while particular embodiments

are illustrated in the drawings, there is no intention to limit the present invention to the specific embodiment or embodiments disclosed. Rather, the present invention is intended to cover all modifications, alternative constructions, and equivalents falling within the spirit and scope of the invention. As such, the drawings are intended to be illustrative and not restrictive.

Unless otherwise defined, all technical terms used herein have the same meaning as commonly understood by one of ordinary skill in the art to which this technology belongs.

Exemplary embodiments of the present invention are depicted in FIGS. 1-4.

The card-like structures and end cap connectors disclosed herein provide a unique yet simple means for building miniature objects in both horizontal and vertical configurations. As utilized herein, the card-like structures and the end cap connectors can be referred to individually and/or collectively as a "connector toy assembly", a "connector toy" or a "toy assembly". Additionally, the various components of the "connector toy assembly", "connector toy" or "toy assembly" can also be referred to generally as a "kit of connector toys" or a "kit of parts".

For the purposes of the present invention, the terminology "corresponds to" means that there is a functional and/or mechanical relationship between objects which correspond to each other. For example, the card-like structures and end cap connectors disclosed herein correspond to each other or mechanically connect with each other when the card-like structure is inserted into the slot or elongated groove on the end cap connector designed to accommodate an end or edge of the card-like structure.

For the purposes of the present invention, the terminology "card-like" means a geometrically shaped sheet or panel such as, without limitation, in the shape of a square or rectangle. The terminology "card-like structure" may be used interchangeably with the terms "card" or "plate" or "plate-like structure" or "sheet" or "sheet-like" or "panel". In certain embodiments, card-like structures will have a flat surface or surfaces or face or faces and will be in a corresponding thickness to fit into a slot or elongated groove of an end cap connector designed for receiving the card-like structure. In an embodiment of the card-like structures disclosed herein, the card-like structures are made of 20 point card stock. As is well established knowledge in the art of paper products, a point is equal to 0.001 inches and is used to indicate a thickness of the paper. In general, the higher the point, the thicker and therefore firmer the paper product.

For the purposes of the present invention, the term "slot" may be interchangeable with the terms "slit" or "groove". In certain embodiments, the card slot is an elongated groove which corresponds to an end or edge of the card-like structure. In one embodiment of the invention disclosed herein, a card-like structure such as a 20 point card stock or the like fits snuggly into a corresponding card slot.

FIGS. 1A-1B show perspective top and bottom views of an embodiment of an 14 end cap connector disclosed herein having 24 slots on the 14T top side (or upper side) only. In this embodiment, the 14 end cap connector additionally has a 18 concentric (protruding) connection pattern on the 14T top side (upper side) of the 14 end cap connector. In other embodiments, such a concentric connection pattern is a Lego® connection pattern. The corresponding (receiving) 22 connection pattern is on the 14B bottom side of the 14 end cap connector. The 24 slots run parallel to 30 edges of the 14 end cap connector that define a 15 perimeter of the 14 end cap connector and correspond in dimension and/or length to the 10 card-like structures which can be fitted into

and/or inserted therein to provide a mechanical connection between the 14 connector and the 10 card-like structure. Upon connective assembly, i.e. a direct coupling, of the 14 end cap connector with another end cap connector (14 or 12 below) a 28 side slot is created. Stated in another manner, each of the 12, 14 end cap connectors include a portion of the 28 side slot. Such a 28 side slot accommodates the 10 card-like structure disclosed herein.

FIGS. 1C-1D show perspective top and bottom views of 10 an embodiment of an 12 end cap connector of the present invention having 26 slots on the 12B bottom side (or underside) only. In this embodiment, the 12 end cap connector has a 18 concentric connection pattern (or nodes) on the 12T top side (upper side) of the 12 end cap connector. 15 The corresponding 22 connection pattern is on the 14B bottom side (underside) of a 14 end cap connector disclosed herein. The 26 slots run parallel to 30 edges of the 12 end cap connector that define a 17 perimeter of the 12 end cap connector and correspond in dimension and/or length to the 20 dimension and/or length of the 10 card-like structures which can be fitted into and/or inserted therein to provide a 25 mechanical connection between the 12 connector and the 10 card-like structure. Upon connective assembly, i.e. a direct coupling, of the 12 end cap connector with an 14 end cap connector a 28 side slot is created. Such a 28 side slot accommodates the 10 card-like structure disclosed herein.

FIG. 2A shows perspective views of exemplary assembly 30 of both 12 and 14 end cap connectors with the 10 card-like structures disclosed herein. FIG. 2B shows a 28 side slot 35 created by the connection between the 12 and 14 end cap connectors. Such a 28 side slot accommodates the card-like structure disclosed herein. Additionally, as illustrated, each of the 10 card-like structures includes a 11 plurality of card edges. For any given 10 card-like structure, one of the 11 40 card edges can be positioned within one of the 24 slots of the 14 end cap connector and an opposed 11 card edge can be positioned within one of the 26 slots of the 12 end cap connector. For example, as shown, an entirety of one of the 11 card edges can be positioned within one of the 24 slots of the 45 14 end cap connector, and an entirety of an opposed 11 card edge can be positioned within one of the 26 slots of the 12 end cap connector. Further, a 11 card edge of one of the 10 card-like structures can also be positioned with the 28 side slot formed when the 14 end cap connector is directly coupled to the 12 end cap connector.

FIG. 3A shows a perspective side view of 12 and 14 end 50 cap connectors combined in such a manner where the 12T top side of 12 end cap connector connects with the 14B bottom side of 14 end cap connector. In this embodiment, the combined configuration of 12 and 14, each having 30 radiused (or rounded) edges, creates a 28 card slot corresponding in dimension and/or length to the dimension and/or length of the 10 card-like structures disclosed herein. FIGS. 3B-3C show perspective side views of 12 and 14 and 16 55 (shown below) end cap connectors combined in such a manner where the top side connects with the corresponding bottom side of the 12 and 14 and 16 end cap connectors. In these embodiments, the combined configuration, having 30 radiused edges creates 24, 26, and/or 28 card slots corresponding in dimension and/or length to the dimension and/or length of the 10 card-like structures disclosed herein.

FIGS. 4A-4B show perspective side, top and bottom (underside) views of an embodiment of an 16 end cap connector of the present invention having 24 slots on the 16T top side (upper side) and 26 slots on the 16B bottom side (under side) and additional 28 slots on the sides or 30 edges of the 16 end cap connector. In one embodiment, the

one or more sides or **30** edges of the **16** end cap connector comprise female and male connective features or connection patterns such as, without limitation, **32** dual concentric protrusions (or nodes) which fit or snap into a corresponding **34** receiving rectangular space providing for connectivity between **16** end cap connectors. Embodiments of end cap connectors such as the **16** end cap connector shown illustrate a wide variety of construction possibilities in both vertical and horizontal configurations. The **10** card-like structures are slotted into and/or fitted therein the **24**, **26**, and/or **28** slots or elongated grooves on the **16** end cap connectors to provide a mechanical connection between the parts of the building set. In one embodiment, the **16B** underside of the **16** end cap connector comprises a triangular configuration of friction points utilizing an **22** open concentric friction point and **36** miniature bar-type friction points to engage with (receive) **18** a (protruding) concentric connection pattern (or node) on the **16T** top side (upper side) of another **16** end cap connector. In one embodiment, there is a 7 by 7 pattern of **18** (protruding) concentric connections or nodes on the **16T** top side (upper side) of an **16** end cap connector. In another embodiment, there is a 9 by 9 pattern of **18** (protruding) concentric connections or nodes on the **16T** top side (upper side) of an **16** end cap connector. In other embodiments, the **10** card-like structure and connector building sets disclosed herein are compatible with existing Lego® or other connection bricks. Exemplary construction is shown in FIG. 4C.

The **10** card-like structures can be inserted into corresponding **24**, **26**, and/or **28** slots of the **12** and **14** and/or **16** end cap connectors. The **24**, **26**, and/or **28** card slots correspond in dimension and/or length to the dimension and/or length of the **10** card-like structure. The **10** card-like structures fit snugly into the corresponding **24**, **26**, and/or **28** card slots. The frictional force resulting from placement of the **10** card-like structure into a corresponding **24**, **26**, and/or **28** card slot of an **12** and **14** and/or **16** end cap connector provides stabilized positioning of the building set components for constructing objects.

The **10** card-like structures and/or **12** and **14** and/or **16** end cap connectors may be provided in a variety of shapes and sizes. In one embodiment, the card slots have a depth of about 2.8 millimeters. In another embodiment, **24**, **26**, and/or **28** card slots are about 2.52 inches wide, the **10** card-like structures are about 2.5 inches wide so that there is about 0.2 inches of clearance to fit a **10** card-like structure into a corresponding **24**, **26**, and/or **28** card slot. In another embodiment, **12** and **14** and/or **16** end cap connector width (not including the protruding nodes or concentric connection pattern) is about 2.8125 inches. In another embodiment, the **24**, **26**, and/or **28** card slots on the **12** and **14** and/or **16** end cap connectors have a depth of about $\frac{3}{16}$ inches. In another embodiment, **12** and **14** and/or **16** end cap connectors are provided in a square shape and measure about 3 inches by 3 inches. In another embodiment, the width of an **12** and **14** and/or **16** end cap connector is about $\frac{1}{4}$ of an inch. In another embodiment, the length of a **24**, **26**, and/or **28** card slot on the **12** and **14** and/or **16** end cap connector is about 2 and $\frac{1}{16}$ inches and the distance between one **24**, **26**, and/or **28** card slot to its opposite **24**, **26**, and/or **28** card slot on the **12** and **14** and/or **16** end cap connector is about 2 and $\frac{1}{2}$ inches. In another embodiment, the width of an **12** and **14** and/or **16** end cap connector is about $\frac{1}{2}$ of an inch. In another embodiment, the **10** card-like structures are provided in a rectangular or square shape and have ends or edges which correspond to the **24**, **26**, and/or **28** card slots on the **12** and **14** and/or **16** end cap connectors in dimension and/or length and/or width.

The **10** card-like structures and/or **12** and **14** and/or **16** connectors may comprise graphics, designs, and/or accompanying character figures. Such character figures may correspond to the provided graphics and/or designs. Graphics, designs and/or characters may include any desired graphic, design, or character whether already known or newly created. Many graphics, designs, and/or characters are well known and may include and/or be inspired from, without limitation, anime, Disney animations, Pixar animations, sports teams, brand names and/or combinations thereof.

The **10** card-like structures and/or **12** and **14** and/or **16** connectors are made of materials well known and readily available to the toy-making industry. Materials may range from a wide variety of available materials such as, without limitation, plastics, laminates, molded plastics, pasteboard or layered pasteboard, paperboard, cardstock, cover stock board stock, paper substrate, foil board, Sintra® PVC foam board, acrylonitrile-butadien-styrene-copolymer (ABS), phthalate-free polyvinyl chloride (PVC), Polyethylene terephthalate glycol-modified (PETG), and/or combinations thereof.

The **10** card-like structures and/or **12** and **14** and/or **16** connectors disclosed herein may additionally incorporate Lego® bricks or other similar compatible building bricks for use in conjunction therewith.

The **10** card-like structures and/or **12** and **14** and/or **16** connectors of the present invention may incorporate reasonable design parameters, features, modifications, advantages, and variations that are readily apparent to those skilled in the art in the field of toy building sets.

Without departing from the scope and spirit of the present invention, reasonable features, modifications, advantages, and design variations of the claimed invention will become readily apparent to those skilled in the art by following the guidelines set forth in the preceding detailed description and embodiments.

What is claimed is:

1. A connector toy assembly comprising:
a plurality of card-like structures including at least a first card-like structure, the first card-like structure including a first card edge;
a rectangle-shaped first end cap connector including (i) a top side, (ii) an opposed bottom side, (iii) a plurality of edges that define a perimeter of the first end cap connector, the plurality of edges extending between the top side and the bottom side, (iv) a plurality of first slots that are formed into the top side of the first end cap connector, each of the plurality of first slots being positioned parallel to two of the plurality of edges and parallel to one other of the first slots, each of the plurality of first slots being configured to receive the first card edge of the first card-like structure, and (v) a first concentric connection pattern formed on the bottom side of the first end cap connector; and
a rectangle-shaped second end cap connector including (i) a top side, (ii) an opposed bottom side, (iii) a plurality of edges that define a perimeter of the second end cap connector, the plurality of edges extending between the top side and the bottom side, (iv) a plurality of second slots that are formed into the bottom side of the second end cap connector, each of the plurality of second slots being positioned parallel to two of the plurality of edges and parallel to one other of the second slots, each of the plurality of second slots being configured to receive the first card edge of the first card-like structure, and (v) a second concentric connection pattern formed on the top side of the second end cap connector;

wherein the first concentric connection pattern is configured to selectively engage the second concentric connection pattern so that the first end cap connector can be selectively directly coupled to the second end cap connector; and

wherein when the first end cap connector is directly coupled to the second end cap connector, each of the plurality of edges of the first end cap connector is positioned directly adjacent to one of the edges of the second end cap connector such that the end cap connectors cooperate to form a plurality of side slots with a first portion of each side slot being formed into one of the edges of the first end cap connector and a second portion of each side slot being formed into one of the edges of the second end cap connector, each of the plurality of side slots being configured to receive the first card edge of the first card-like structure.

2. The connector toy assembly of claim 1 wherein each of the plurality of first slots is configured to receive an entirety of the first card edge.

3. The connector toy assembly of claim 1 wherein each of the plurality of second slots is configured to receive an entirety of the first card edge.

4. The connector toy assembly of claim 1 wherein each of the plurality of side slots is configured to receive an entirety of the first card edge.

5. A connector toy assembly comprising:

a plurality of card-like structures including at least a first card-like structure, the first card-like structure including a first card edge and an opposed second card edge;

a one-piece, rectangle-shaped, first end cap connector including (i) a top side, (ii) an opposed bottom side, (iii) four edges that define a perimeter of the first end cap connector, the four edges extending between the top side and the bottom side, (iv) four first slots that are formed into the top side, each of the first slots being positioned parallel to two of the four edges and parallel to one other of the first slots of the first end cap connector, each of the first slots being positioned spaced apart from the perimeter of the first end cap connector, and each of the first slots being positioned spaced apart from each of the other first slots of the first end cap connector, (v) four second slots that are formed into the bottom side, each of the second slots being positioned parallel to two of the four edges and parallel to one other of the second slots of the first end cap connector, each of the second slots being positioned spaced apart from the perimeter of the first end cap connector, and each of the second slots being positioned spaced apart from each of the other second slots of the first end cap connector, (vi) four side slots, with one side slot being formed into each of the four edges of the first end cap connector, (vii) a male concentric connection pattern formed on the top side of the first end cap connector between the four first slots, (viii) a female concentric connection pattern formed on the bottom side of the first end cap connector between the four second slots, and (ix) a pair of concentric protrusions that extend away from one of the four edges of the first end cap connector; wherein each of the first slots, each of the second slots, and each of the side slots is sized and shaped to receive one of the first card edge and the second card edge of one of the plurality of card-like structures; and

a one-piece, rectangle-shaped, second end cap connector including (i) a top side, (ii) an opposed bottom side, (iii) four edges that define a perimeter of the second end cap

connector, the four edges extending between the top side and the bottom side, (iv) four second side slots, with one second side slot being formed into each of the four edges of the second end cap connector, and (v) a receiving rectangular space that is formed into one of the four edges of the second end cap connector;

wherein the receiving rectangular space is configured to selectively receive the pair of concentric protrusions to selectively connect the first end cap connector to the second end cap connector;

wherein one of the side slots of the first end cap connector extends through the pair of concentric protrusions; and wherein one of the second side slots of the second end cap connector extends through the receiving rectangular space.

6. The connector toy assembly of claim 5 wherein the first end cap connector further includes a receiving rectangular space that is formed into one of the four edges of the first end cap connector; wherein the second end cap connector further includes a pair of concentric protrusions that extend away from one of the four edges of the second end cap connector; and wherein the receiving rectangular space is configured to selectively receive the pair of concentric protrusions to selectively connect the first end cap connector to the second end cap connector.

7. The connector toy assembly of claim 6 wherein one of the side slots of the first end cap connector extends through the receiving rectangular space; and wherein one of the second side slots of the second end cap connector extends through the pair of concentric protrusions.

8. The connector toy assembly of claim 5:

wherein the plurality of card-like structures includes the first card-like structure, a second card-like structure, a third card-like structure and a fourth card-like structure, each card-like structure including a first card edge and an opposed second card edge;

wherein the second end cap connector further includes (i) four first slots that are formed into the top side, each of the first slots being positioned parallel to two of the four edges and parallel to one other of the first slots of the second end cap connector, each of the first slots being positioned spaced apart from the perimeter of the second end cap connector, and each of the first slots being positioned spaced apart from each of the other first slots of the second end cap connector, and (ii) four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector;

wherein one of the first slots of the first end connector is configured to receive the first card edge of the first card-like structure, and one of the second slots of the second end connector is configured to receive the second card edge of the first card-like structure;

wherein another of the first slots of the first end connector is configured to receive the first card edge of the second card-like structure, and another of the second slots of the second end connector is configured to receive the second card edge of the second card-like structure;

wherein still another of the first slots of the first end connector is configured to receive the first card edge of the third card-like structure, and still another of the

second slots of the second end connector is configured to receive the second card edge of the third card-like structure; and

wherein yet another of the first slots of the first end connector is configured to receive the first card edge of the fourth card-like structure, and yet another of the second slots of the second end connector is configured to receive the second card edge of the fourth card-like structure.

9. The connector toy assembly of claim 5 wherein the second end cap connector further includes (i) four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector, and (ii) a female concentric connection pattern formed on the bottom side between the plurality of second slots; and wherein the male concentric connection pattern formed on the top side of the first end cap connector is configured to selectively engage the female concentric connection pattern formed on the bottom side of the second end cap connector so that the first end cap connector can be selectively directly coupled to the second end cap connector.

10. The connector toy assembly of claim 5 wherein the second end cap connector further includes (i) four first slots that are formed into the top side, each of the first slots being positioned parallel to two of the four edges and parallel to one other of the first slots of the second end cap connector, each of the first slots being positioned spaced apart from the perimeter of the second end cap connector, and each of the first slots being positioned spaced apart from each of the other first slots of the second end cap connector, and (ii) a male concentric connection pattern formed into the top side between the plurality of first slots; and wherein the female concentric connection pattern formed on the bottom side of the first end cap connector is configured to selectively engage the male concentric connection pattern formed on the top side of the second end cap connector so that the first end cap connector can be selectively directly coupled to the second end cap connector.

11. The connector toy assembly of claim 5 wherein the second end cap connector further includes four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector, and wherein the first card edge is positioned in one of the first slots of the first end cap connector, and wherein the second card edge is positioned in one of the second slots of the second end cap connector.

12. The connector toy assembly of claim 5 wherein the first card edge is positioned in one of the side slots of the first end cap connector, and wherein the second card edge is positioned in one of the second side slots of the second end cap connector.

13. A connector toy assembly comprising:
a plurality of card-like structures including at least a first card-like structure, the first card-like structure including a first card edge and an opposed second card edge; 65 a one-piece, rectangle-shaped, first end cap connector including (i) a top side, (ii) an opposed bottom side, (iii)

four edges that define a perimeter of the first end cap connector, the four edges extending between the top side and the bottom side, (iv) four first slots that are formed into the top side, each of the first slots being positioned parallel to two of the four edges and parallel to one other of the first slots of the first end cap connector, each of the first slots being positioned spaced apart from the perimeter of the first end cap connector, and each of the first slots being positioned spaced apart from each of the other first slots of the first end cap connector, (v) four second slots that are formed into the bottom side, each of the second slots being positioned parallel to two of the four edges and parallel to one other of the second slots of the first end cap connector, each of the second slots being positioned spaced apart from the perimeter of the first end cap connector, and each of the second slots being positioned spaced apart from each of the other second slots of the first end cap connector, (vi) four side slots, with one side slot being formed into each of the four edges of the first end cap connector, (vii) a male concentric connection pattern formed on the top side of the first end cap connector between the four first slots, (viii) a female concentric connection pattern formed on the bottom side of the first end cap connector between the four second slots, and (ix) a receiving rectangular space that is formed into one of the four edges of the first end cap connector; wherein each of the first slots, each of the second slots, and each of the side slots is sized and shaped to receive one of the first card edge and the second card edge of one of the plurality of card-like structures; and

a one-piece, rectangle-shaped, second end cap connector including (i) a top side, (ii) an opposed bottom side, (iii) four edges that define a perimeter of the second end cap connector, the four edges extending between the top side and the bottom side, (iv) four second side slots, with one second side slot being formed into each of the four edges of the second end cap connector, and (v) a pair of concentric protrusions that extend away from one of the four edges of the second end cap connector; wherein the receiving rectangular space is configured to selectively receive the pair of concentric protrusions to selectively connect the first end cap connector to the second end cap connector;

wherein one of the side slots of the first end cap connector extends through the pair of concentric protrusions; and wherein one of the second side slots of the second end cap connector extends through the receiving rectangular space.

14. The connector toy assembly of claim 13 wherein the first end cap connector further includes a pair of concentric protrusions that extend away from one of the four edges of the first end cap connector; wherein the second end cap connector further includes a receiving rectangular space that is formed into one of the four edges of the second end cap connector; and wherein the receiving rectangular space is configured to selectively receive the pair of concentric protrusions to selectively connect the first end cap connector to the second end cap connector.

15. The connector toy assembly of claim 13:
wherein the plurality of card-like structures includes the first card-like structure, a second card-like structure, a third card-like structure and a fourth card-like structure, each card-like structure including a first card edge and an opposed second card edge;

11

wherein the second end cap connector further includes (i) four first slots that are formed into the top side, each of the first slots being positioned parallel to two of the four edges and parallel to one other of the first slots of the second end cap connector, each of the first slots being positioned spaced apart from the perimeter of the second end cap connector, and each of the first slots being positioned spaced apart from each of the other first slots of the second end cap connector, and (ii) four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector;

wherein one of the first slots of the first end connector is configured to receive the first card edge of the first card-like structure, and one of the second slots of the second end connector is configured to receive the second card edge of the first card-like structure; wherein another of the first slots of the first end connector is configured to receive the first card edge of the second card-like structure, and another of the second slots of the second end connector is configured to receive the second card edge of the second card-like structure; wherein still another of the first slots of the first end connector is configured to receive the first card edge of the third card-like structure, and still another of the second slots of the second end connector is configured to receive the second card edge of the third card-like structure; and

wherein yet another of the first slots of the first end connector is configured to receive the first card edge of the fourth card-like structure, and yet another of the second slots of the second end connector is configured to receive the second card edge of the fourth card-like structure.

16. The connector toy assembly of claim 13 wherein the second end cap connector further includes (i) four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector, and (ii) a female concentric connection pattern formed on the bottom side between the plurality of second slots; and wherein the male concentric connection pattern formed on the top side of the first end cap connector is configured to selectively engage the female concentric connection pattern formed on the bottom side of the second end cap connector so that the first end cap connector can be selectively directly coupled to the second end cap connector.

17. The connector toy assembly of claim 13 wherein the second end cap connector further includes (i) four first slots that are formed into the top side, each of the first slots being positioned parallel to two of the four edges and parallel to one other of the first slots of the second end cap connector, each of the first slots being positioned spaced apart from the perimeter of the second end cap connector, and each of the first slots being positioned spaced apart from each of the other first slots of the second end cap connector, and (ii) a male concentric connection pattern formed into the top side

12

between the plurality of first slots; and wherein the female concentric connection pattern formed on the bottom side of the first end cap connector is configured to selectively engage the male concentric connection pattern formed on the top side of the second end cap connector so that the first end cap connector can be selectively directly coupled to the second end cap connector.

18. The connector toy assembly of claim 13 wherein the second end cap connector further includes four second slots that are formed into the bottom side, each of the second slots being positioned parallel to two of the four edges and parallel to one other of the second slots of the second end cap connector, each of the second slots being positioned spaced apart from the perimeter of the second end cap connector, and each of the second slots being positioned spaced apart from each of the other second slots of the second end cap connector, and wherein the first card edge is positioned in one of the first slots of the first end cap connector, and wherein the second card edge is positioned in one of the second slots of the second end cap connector.

19. The connector toy assembly of claim 13 wherein the first card edge is positioned in one of the side slots of the first end cap connector, and wherein the second card edge is positioned in one of the second side slots of the second end cap connector.

20. A connector toy assembly comprising:
a plurality of card-like structures including at least a first card-like structure, the first card-like structure including a first card edge and an opposed second card edge; a one-piece, rectangle-shaped, first end cap connector including (i) a top side, (ii) an opposed bottom side, (iii) four edges that define a perimeter of the first end cap connector, the four edges extending between the top side and the bottom side, (iv) four first slots that are formed into the top side, each of the first slots being positioned parallel to two of the four edges and parallel to one other of the first slots of the first end cap connector, each of the first slots being positioned spaced apart from the perimeter of the first end cap connector, and each of the first slots being positioned spaced apart from each of the other first slots of the first end cap connector, (v) four second slots that are formed into the bottom side, each of the second slots being positioned parallel to two of the four edges and parallel to one other of the second slots of the first end cap connector, each of the second slots being positioned spaced apart from the perimeter of the first end cap connector, and each of the second slots being positioned spaced apart from each of the other second slots of the first end cap connector, (vi) four side slots, with one side slot being formed into each of the four edges of the first end cap connector, (vii) a male concentric connection pattern formed on the top side of the first end cap connector between the four first slots, (viii) a female concentric connection pattern formed on the bottom side of the first end cap connector between the four second slots, (ix) a pair of concentric protrusions that extend away from one of the four edges of the first end cap connector, and (x) a receiving rectangular space that is formed into one of the four edges of the first end cap connector;

wherein each of the first slots, each of the second slots, and each of the side slots is sized and shaped to receive one of the first card edge and the second card edge of one of the plurality of card-like structures; wherein one of the side slots of the first end cap connector extends through the pair of concentric protrusions; and

wherein one of the side slots of the first end cap connector
extends through the receiving rectangular space.
